UNITED STATES PATENT OFFICE

FREDERICK WILLIAM VICKERY, OF LONDON, ENGLAND, ASSIGNOR TO VICKERY INCORPORATED, A CORPORATION OF MASSACHUSETTS

DOCTOR FOR PAPER-MAKING AND LIKE MACHINES

Application filed June 13, 1931, Serial No. 544,119, and in Great Britain July 31, 1930.

This invention relates to doctors for the rolls of paper-making and like machines and particularly to the fastening of their blades. In the older forms of doctor the 5 blade is fastened directly upon a rigid carrier mounted in the machine frame. In modern doctors the blade is commonly slid endwise into a slot or groove in a support, and is pressed upon the roll by resilient 10 means which may constitute the support or may be additional to it. By these constructions the blade is enabled to bend lengthwise throughout its width, and so its edge can maintain an even pressure on the roll notwithstanding irregularities in the roll or 15 movements of it relatively to the doctor carrier. Only at the ends is there any means for retaining the blade in its slot, and consequently it is liable to spring out of position if it is pressed upon the roll with undue 20 force.

One purpose of this invention is to secure the blade against such dislodgement from its support, even under excessive working 25 pressure, without diminishing the flexibility attained by modern constructions. A further purpose of the invention is to enable the blade to be safely removed and replaced while the paper-making machine is running.

30 With these ends in view the invention provides for attaching the blade to its support by means of enlargements or projections in the thickness of the blade lodged in an undercut slot in the support from which 35 they can be disengaged only by endwise movement. Such enlargements or projections must be of small dimensions especially in the lengthwise direction of the blade in order that they may not interfere with the 40 bending of the blade.

As the blade is often made of tempered steel it is best to attach separate enlargements to it; a convenient method is to fasten studs in pairs at intervals along the rear 45 edge of the blade; one stud of each pair being on one side and one on the other.

The use of such an attachment excludes the possibility of the blade being dislodged by undue pressure. Moreover it enables the 50 blade to be removed and replaced without

danger while the paper-making machine is running. The same method of attachment may be applied in some cases to the resilient means which press the doctor blade upon the roll, so that these, too, can be interchanged 55 without stopping the machine.

Examples of constructions embodying the invention are shown in the accompanying drawings.

Figure 1 is a transverse section of a doctor 60 in which the blade is carried in spring fingers, substantially as has been described in my former Patent No. 1,552,363.

Figure 2 is a similar view of a modification in which stiff fingers yieldably connected with the carrier are employed.

Figure 3 is an edge view of a blade showing a preferred form of enlargements or projections.

Figure 4 is an edge view of the slotted 70 supports.

Figures 5, 6 and 7 are transverse sections of constructions in which both the blade and the resilient means by which it is pressed upon the roll are held in the support by projections engaging in undercut slots.

In Figure 1 the blade 1 is carried upon a spring plate or a number of spring fingers 2 as described in my former patent above mentioned. But instead of the rear edge 80 of the blade being received in a simple slot or groove between the spring finger and the head of a stud secured in the finger, it is fitted with projections or enlargements 3 which are received in an undercut slot 4 85 formed in a support or holder 5 attached to the spring finger. A bar of the section shown may readily be produced by extrusion and cut into suitable lengths; these are fastened one to each finger if the resilient support consists of spring fingers, or are spaced apart along the edge of the spring plate if the support is a single plate. Preferably the slot 4 presents a rear ledge 6 on which the rear edge of the blade rests.

Figure 2 is a similar view of a modification in which the holder 5 includes a stiff finger portion 7 resiliently supported from the doctor carrier 8 by a spring plate 9 or a series of spring fingers.

As appears from the edge view of the blade in Figure 3 the enlargements 3 may consist of studs, or preferably of pairs of rivets passed through the blade at intervals 5 along its length, the head of one rivet of each pair being above the blade and the head of the other below the blade. The use of pairs of rivets renders less care necessary in setting up the tail of the rivet; in any 10 case they need not be tight. These rivet heads are too large to pass through the mouth 10 of the slot 4, so that the blade cannot snap out of the holder whatever pressure is applied to it, but can only be 15 withdrawn lengthwise when the doctor has been lifted from the roll. If the holders 5 or 7 are spaced apart and the pairs of rivets 3 are correspondingly spaced it is not necessary to move the blade lengthwise a distance 20 equal to its length in order to withdraw it; it may be moved lengthwise sufficiently to disengage each pair of rivets from the holder in which it lies, and then removed in the direction of its width. In this case 25 means, such as are already known, must be provided to prevent any considerable lengthwise movement of the blade during working. If it is preferred that the blade should be removable only by complete lengthwise 30 withdrawal, the pairs of rivets 3 are so spaced that when one registers with a gap between the fingers and is therefore free, a neighbouring pair is still engaged in a slotted holder.

In such an arrangement, or if the holders 7 are in close proximity, as indicated in the edge view of them in Figure 4, so that the blade must be inserted and removed wholly by lengthwise movement, it is desirable to 40 provide means, such as the studs 11 at the edge of each finger overlapping the next, to prevent undue displacement of one finger with respect to the other; and it is also desirable to flare the ends 12 of the mouth 10 of the undercut slot, so that these still overlap when neighbouring fingers have the maximum relative displacement allowed by the studs 11. These means ensure that a 45 blade thrust in from one end will find its way through the undercut slot from finger to finger and not be stopped by abutting against a displaced finger.

Figure 5 shows a construction in which not only the blade but also the resilient 55 means by which it is pressed upon the roll, are held in the manner above described. The extruded bar 15 forming the support is attached directly to the carrier 22. In it are two undercut slots 4, 16, the latter lying 60 above and in the rear of the former in position to receive a spring plate 17 (or a series of spring fingers) which bears upon the blade 1 and is retained in the slot 16 by enlargements 18. These may in this case be 65 continuous bars, but preferably are rivets as in

already described. It will be seen that the mouth 10 of the slot 4 limits the extent to which the blade 1 can be deflected, and so hinders the spring 17 being overstrained. Should the spring, however, become permanently deformed it can be removed and inserted the reverse way, or replaced by another while the machine is working.

Figure 6 shows a slight modification of this construction in respect of the attachment of the blade 1. A large part of the upper wall of the slot 4 is omitted and deflection of the blade 1 is limited not by the mouth of the slot 4 but by the narrow groove 23 in which the rear edge of the blade is inserted. This groove in fact embraces the edge of the blade somewhat more closely than the drawings can conveniently show. The groove also prevents the blade 1 being pressed upwards sufficiently to release the 80 projections 3. Thus in this case the projections 3 do not alone wholly perform the function of retaining the blade but with the rear edge of the blade they constitute an 85 enlargement which is confined within a somewhat more complex form of undercut slot made up of the principal slot 4 and the groove 23.

Figure 7 shows a construction like that of Figure 5 for use where the resilient means of pressing the blade upon the roll consists of a strip of rubber 19. This strip can also be made by extrusion, and is formed with a narrow neck 20 and an enlargement 21 to be retained in the slot 16.

I claim:

1. In a doctor the combination of a renewable blade, resilient means for supporting said blade while permitting it to bend throughout its width, said means being formed with an undercut slot, and thickenings in said blade of small dimension in its lengthwise direction adapted to enter said undercut slot by lengthwise movement but not releasable by movement at right angles.

2. A renewable blade for doctors comprising a flexible strip having projections in its thickness of small lengthwise dimension spaced at intervals along its length.

3. A renewable blade for doctors comprising a flexible strip, and pairs of rivets spaced at intervals along its length, the rivets of a pair having their heads on opposite sides of the blade.

4. In a doctor, a blade support comprising a number of resiliently yielding fingers presenting at their ends aligned undercut slots flared at their ends, and means for limiting the relative movement of said fingers to the width of the flare.

5. In a doctor the combination of a blade, a blade support having an undercut slot therein, a resilient plate, an enlargement upon one edge of said plate adapted to engage in said undercut slot so as to be removable

only by endwise movement while the other edge of said plate bears on said blade.

6. In a doctor the combination of a support having two undercut slots therein, a 5 blade having enlargements thereon adapted to engage in one of said undercut slots and to be releasable only by endwise movement, and a resilient plate having enlargements thereon adapted similarly to engage in the 10 other undercut slot while the plate bears upon the blade.

7. In a doctor the combination of a blade carrying projections, a support having an undercut slot to receive the edge of said 15 blade and its projections and to limit the yield of said blade, and resilient means attached to said support and bearing upon said blade.

8. In a doctor, a blade support comprising 20 a resiliently yielding member with a series of short holders attached thereto presenting at its edge aligned undercut slots.

9. In a doctor, a blade support comprising a number of resiliently yielding fingers with 25 short holders attached to individual fingers presenting at their ends aligned undercut slots.

10. In a doctor the combination of a blade carrying projections, a support having an undercut slot to receive and retain the edge 30 of said blade and its projections, and resilient means attached to said support and bearing upon said blade.

In testimony whereof I have signed my 35 name to this specification.

FREDERICK WILLIAM VICKERY.
